UNITED STATES PATENT OFFICE.

ALLEN A. TIRRILL, OF SCHENECTADY, NEW YORK.

ELECTRIC SWITCH.

1,142,859.

Specification of Letters Patent. Patented June 15, 1915.

Application filed October 28, 1909. Serial No. 525,226.

To all whom it may concern:

Be it known that I, ALLEN A. TIRRILL, a citizen of the United States, residing at Schenectady, in the county of Schenectady and State of New York, have invented certain new and useful Improvements in Electric Switches, of which the following is a specification, reference being had therein to the accompanying drawing.

10 This invention relates to improvements in electric switches, and more particularly snap switches of that general type disclosed in my U. S. Letters Patents Nos. 819,821 and 819,822 of May 8, 1906.

15 Primarily the switch of the present invention is designed especially for use as a ceiling switch, adapted to be manipulated through the medium of a suspended cord or chain to control lighting circuits, but it is capable of use in other respects and places as will be apparent to those skilled in the art.

20 Advantageous characteristics of the improvements reside in the simplification of the operating mechanism of the switch, the rendering of the same more efficient in operation, and the reduction of the expense of manufacture.

25 The novel details in the construction and arrangement of parts of a structure made in keeping with the invention will be apparent from the detailed description hereinafter contained, when read in connection with the accompanying drawings forming part hereof and wherein a convenient embodiment of the invention is illustrated. It is to be understood, however, that the invention is not to be restricted to the specific embodiment disclosed herein, because, as will be obvious, other embodiments may be resorted to without in the least departing from the spirit of the invention.

30 In the drawings, Figure 1 is a perspective view of the complete device as secured to a ceiling; Fig. 2 is a sectional view through the insulated base and cap or cover, the operating mechanism being shown in end elevation with the rear rotatable switch knife or blade in inactive position; Fig. 2^a is an enlarged fragmentary sectional view of the cap showing the manner of securing the insulating lining within the metallic cover; Fig. 3 is a side elevation of the operating mechanism (the cover being removed) looking from the right of Fig. 2; Fig. 4 is a bottom view of Fig. 3, Fig. 5 is

an enlarged longitudinal section of the operating mechanism, Fig. 6 is a face view of one of the switch knives or blades showing the insulation for the sides thereof. Fig. 7 is a view similar to Fig. 6 with the side insulation removed to show the interior insulating member of the blade mounting; Fig. 8 is a transverse section of the device taken on the line 8—8, Fig. 5, looking in the direction of the arrow; Fig. 9 is also a transverse section taken on the line 9—9 of Fig. 5, looking in the direction of the arrow; Fig. 10 is still another transverse sectional view on the line 10—10 of Fig. 5, looking in the direction of the arrow; Fig. 11 is a detail perspective view of one of the spring contact devices; Fig. 12 is a perspective view of one of the combined contact supports and wire terminal securing devices; Fig. 13 is a detail perspective view showing the detachable securing device at the end of the operating cord or chain, Fig. 14 is a fragmentary peripheral view of the rotatable sheave showing in full lines the manner of attaching the cord securing device thereto and in dotted lines the operating position which the same assumes, and Fig. 15 is a detail view of the pivoted detent.

35 Referring more specifically to the drawings wherein like reference characters designate corresponding parts in the several views, A represents the ordinary ceiling to which my switch is usually secured through the medium of bolts B passing through a porcelain or other suitable base C of insulating material. Secured by means of screws d to the base C and suitably spaced apart are brackets D conveniently formed of sheet metal and apertured as at d' for the accommodation of a switch blade carrying shaft E. The end portions of the shaft are of angular cross section, represented at e to form a shoulder e', the extreme ends being grooved as at e² for the reception of a washer F, the washer being fastened in place by pinching the ends thereof together as shown in Fig. 2. Intermediate the shoulders e' and the washers F at the opposite ends of the shaft are mounted a pair of switch blades G, the mounting of which will be hereinafter referred to. It is desirable that these switches be insulated from the shaft E, and to that end the interior of the former are formed hollow, as at g for the reception of an insulating member g' immediately surrounding the shaft. At the opposite sides of

the insulating member g' and of a size greater than said member whereby to lap over the same and to some extent overlie the opposite surfaces of the blades G are other insulating members g^2 , the whole being secured together by means of rivets h passing through plates H and through aligned apertures in the insulating members as is clearly illustrated in Fig. 5, the blades G being rigidly clamped in position by the opposite insulating members g^2 and plates H . As illustrated, each blade has oppositely disposed outwardly extending contact extensions adapted to enter between and engage separated spring contacts I , it being observed that the space between the shoulder e' on the shaft and the washer F is greater than the combined width of the switch blade and its mounting, whereby the latter may have a substantial freedom of movement to enable the same to be bodily shifted automatically, or be self-adjusting, to allow for any possible disalignment of opposite pairs of spring contacts and to insure each blade extension having engagement on its opposite surfaces with both branches or arms of its spring contact device. The spring contacts just referred to are conveniently formed of spring metal, the branches I being arranged parallel with their ends flared somewhat to facilitate the entrance of the blade g therebetween, the branches being connected by bowed spring portions i and secured in place through the medium of struck-in flanges i' adapted to embrace an upright K to which latter the same is secured by means of a rivet i^2 passing through the flanges i' and said upright. Of course in some instances the blade may be double and flexible and the contact device single, which would constitute a mechanically reverse arrangement to that shown and described herein.

The upright K in turn is provided with a securing base portion k secured to the porcelain base C by screws k' passing through apertures k^2 therein. A large opening k^3 is provided in the base k for the reception of a binding screw k^4 adjoining a pair of struck up lugs k^5 around which and beneath the head of the screw the wire terminals (not necessary to herein show) passing through openings c in the base C , are secured. In order to permit the uprights K to occupy the least possible space whereby to lessen the size of the area required to accommodate the entire device, said uprights are offset inwardly intermediate the ends of the same, as at k^6 .

The means for effecting the quick or snap action of the switch will now be defined. Mounted loosely upon the shaft E is a sheave L carrying a bushing l projecting axially thereof and surrounding the shaft. The sheave is conveniently formed of sheet metal having a grooved flange l' to guide an oper-

ating pull cord or chain L' , the latter being secured to the sheave by means of a slotted flange l^2 on the sheave in which enters an offset T-head l^3 clamped to the end of the cord L' through the medium of a compressed and indented ferrule l^4 . The insertion of the head in the slotted flange is clearly shown in full lines, Fig. 14, and its secured or operating position at right angles thereto in dotted lines in the same figure. This arrangement affords a simple and efficient detachable connection between the operating cord or chain and the sheave. The sheave also has a projecting lug l^5 adapted to contact notched portions d^3 in one of the uprights D to limit the rotation of the sheave in either direction. The sheave further has a struck up outwardly arched hook l^6 for confining the cord L' in the grooved portion l' thereof.

The sheave normally occupies the position shown in Fig. 5 with the stop lug l^5 in engagement with the lower end of the upright D , this position being maintained by means of a spring M secured at one end m to the upright D , and at its opposite end m' abutting an offset tail-piece m^2 of a pawl M' presently to be described, arranged at the opposite side of the sheave and pivoted thereto, as at m^3 . The pawl M' engages a ratchet disk N also loose upon the shaft and the function of the spring M is not only to hold the sheave in the position shown in Fig. 5 and to return the same to such position when moved therefrom as will hereinafter appear, but also incident to the engagement of the spring at m , m^2 to retain the pawl M' normally in engagement with a tooth of the ratchet disk N .

What I will term the motor spring is shown at O engaged at one end o with the ratchet disk N and at its other end against an offset lug p of a detent carrier P fixed to the shaft and normally held against rotation under the force of the motor spring because of the engagement of the detent P' with one of the stop shoulders q of a fixed disk Q secured by pins q' to the adjacent upright D . Normally the detent is retained in engagement with the shoulder q just referred to by means of a cam plate R through the slot r of which a lug p' offset from the detent P' projects, the cam plate in turn being held against excessive movement in either direction by means of shoulders r' adapted to abut the offset lug p of the detent carrier before referred to.

The operation of the mechanism thus far described may now be followed. Assuming the parts to be in a position indicated by the several views of the drawings, and it being desired to close any of a given number of circuits dependent upon the wiring of the base members k of the spring contact supports K , it will simply be necessary to

mentioned insulating member and the opposite faces of the metal switch blade, and clamping means passing through said insulating plates and the interposed insulating member, said clamping means being positioned within the opening in the central portion of the metallic switch blade.

2. An electrical switch comprising a shaft, a stationary ratchet having teeth and adjacent recesses, a pawl carried by the shaft, a cam that moves the pawl into and out of engagement with the teeth of the ratchet and also into and out of the recesses therein, to permit of the shaft being advanced and stopped and to positively lock it in stationary position, and means for actuating the cam and the shaft.

3. An electrical switch comprising a shaft, a stationary ratchet having teeth and adjacent recesses, a pawl carried by the shaft having an extension, a member loosely mounted on the shaft having a cam slot to receive the pawl extension, the said member serving to move the pawl into and out of engagement with the teeth of the ratchet and also into and out of the recesses therein, to permit of the shaft being advanced and stopped and to positively lock it in stationary position, means for actuating the cam, and resilient means for actuating the shaft.

4. In a switch of the character described, a base, a plurality of laterally spaced contacts supported by said base, a shaft supported by said base and positioned in a plane parallel to the plane of the base, said shaft being provided at separated points with squared portions, and a pair of switch blades loosely mounted on the squared portions of said shaft, so as to rotate with said shaft to coöperate with said contacts, the squared portions of the shaft being of a length to permit each of said blades to move independently of the other longitudinally of the shaft.

5. In a rotary switch of the character described, a base, a plurality of contact devices carried thereby, the contact surfaces of said contacts being perpendicular to the plane of the base, a transversely disposed shaft carried by said base, switch blades carried by said shaft and positioned in planes at right angles to the longitudinal axis thereof, said switch blades being adapted to coöperate with the contact devices carried by the base upon rotation of the shaft, and means for imparting a step by step rotation to said shaft, said means including a sheave mounted thereon and a pull cord depending from said sheave.

6. In a switch of the character described, contact devices and means for operating the same, including a shaft, a rotatable sheave, a ratchet wheel, a pawl carried by said sheave and adapted to coöperate with said ratchet

wheel, and a spring for shifting said sheave and for holding said pawl in engagement with its ratchet wheel.

7. In a switch, a base, a pair of laterally spaced contact members carried by said base, a rotatable shaft supported by said base, a pair of laterally separated switch blades on said shaft, each of said blades being rotatable with the shaft and being free to move for a limited distance longitudinally of said shaft, and each of said blades being adapted to coöperate with one of the contacts carried by the base, and means mounted directly on the shaft between the switch blades carried thereby, for imparting a step by step rotation to the shaft.

8. In a switch, a base, contacts carried thereby, a rotatable shaft supported by said base, switch blades carried by said shaft and rotatable therewith, a sheave loosely mounted on said shaft, means for actuating said sheave, means tending to return the sheave to normal position when actuated, a ratchet wheel loosely mounted on said shaft at one side of said sheave, a pawl carried by said sheave and adapted to engage said ratchet wheel, a detent carrier fixedly secured to said shaft, a movable detent secured to said detent carrier and normally engaging a fixed member to prevent movement of said detent carrier and said shaft in either direction, a motor spring connecting said ratchet wheel and detent carrier, and means for releasing said detent after a predetermined extent of movement of said ratchet wheel.

9. In a switch, a base, a rotatable shaft supported by said base, switch blades carried by said shaft and rotatable therewith, a sheave loosely mounted on said shaft, means for actuating said sheave, means tending to return the sheave to normal position when actuated, a ratchet wheel loosely mounted on said shaft, a pawl carried by said sheave and adapted to engage said ratchet wheel, a cam plate movable with said ratchet wheel and provided with a cam slot therein, a detent carrier fixedly secured to said shaft at one side of said cam plate, a disk fixedly supported from said base and surrounding the shaft, said disk being provided with a plurality of notches in the periphery thereof having oppositely arranged straight walls, a pivoted detent carried by said detent carrier and adapted to engage one of the notches in said disk, said detent being provided with a portion engaging the cam slot in the cam plate, and a motor spring connecting the ratchet wheel and said detent carrier.

10. In a switch, a base, contacts carried thereby, a rotatable shaft supported by said base, switch blades carried by said shaft and rotatable therewith, a sheave loosely mounted on said shaft, means for actuating said sheave, means tending to return the sheave to normal position when actuated, a ratchet

pull upon the cord or chain L' to store up power in the motor spring O and by the co-operation of the several devices to permit said motor spring to exercise its energy and 5 rotate the switch blades G with a quick snap action to engage or by progressive rotary movement to alternately engage and disengage or make and break contact with the spring contact devices I . More specifically, the pull upon the cord or chain L' rotates the sheave in the direction of the arrow Figs. 2 and 8, and the pawl M' carried therewith and engaging one of the teeth of the ratchet N rotates the latter in the same 15 direction, the rotation of the sheave being of course against the tension of its restoring spring M . This rotation of the ratchet disk N winds up the motor spring O , one end of which spring is connected to the 20 ratchet disk N and the other end abutting the fixed lug p of the detent carrier P , which latter cannot move at this time by reason of the engagement of the detent P' with the fixed stop disk at q . The cam 25 plate R being connected to the ratchet disk N rotates the said disk in the direction of the arrow, Fig. 8, and by means of the cam-way or groove r thereof engaging with the offset lug p' of the detent P' gradually elevates the detent out of engagement with the shoulder q , the parts being so proportioned and timed in their operation that the motor spring O will have the desired power or 30 energy stored up therein at the time the detent leaves said shoulder. Practically instantaneously upon the disengagement of the detent P' from the shoulder q the detent carrier P is released and under the action of the motor spring O in engagement 35 with the offset p thereof shifts said carrier around one-fourth of a revolution or until the lug p' of the detent is guided by the cam way r into engagement with the next adjacent stop shoulder q of the fixed plate Q . The 40 carrier P being keyed to the shaft E rotates said shaft therewith and throws the switch blades G into or out of engagement with the spring contact devices I as the case may be, the free mounting of the switch blades enabling them to adjust themselves to the 45 spring contacts as hereinabove described.

After the operation just stated and upon the release of the cord L' the sheave will be returned under the action of its spring M to its initial position. The travel of the sheave in its forward movement being approximately 90° , the switch blades will alternately make and break contact with the spring jaws. When contacting with the jaws, the friction incident to the clamping action is sufficient to ordinarily overcome any tendency of the shaft and blades to turn backward from their advanced position with the sheave. On the other hand, when 50 not in contacting engagement the blades are 55

relatively free and might turn back with the sheave and again make contact when not desired were it not for the means positively preventing such movement and to which I will now refer. In the stop ratchet Q there is formed an angular or notched portion Q' immediately adjoining each shoulder q into which a correspondingly angular heel q^2 on the detent P' will fit and engage and thus be positively prevented from moving backward after it has been once advanced into engagement with the successive stop shoulders. Therefore the stop disk Q serves the double purpose of limiting the advancing movement of the detent P' and associated parts including the shaft and switch blades and of preventing reverse rotation of said parts after the completion of a step in the progressive operation of the switch. 70 75 80 85

The whole of the apparatus is inclosed by an insulated cap or cover S held in place by means of a screw s passing therethrough and into engagement with a threaded aperture s' in the lower end of the bracket D , the cap being held in proper relation to the actuating parts and the suspended cord L' which passes through a rounded hollow rivet T therein by means of a lug u on the porcelain base C adapted to enter a notch U in the upper edge of the cover. The insulation of the cover is formed in two pieces (note Fig. 2^a), one being a shallow cup V and the other a split cylinder W . The portion V is held in position by means of the hollow rivet T which also forms a rounded edge bearing for the cord L' and the split cylindrical portion W is retained in position by means of a tongue w struck inwardly from the metal of the cap or cover and over the notched edge w' of the lining which adjoins the notch U in the cover. The insulation extends outwardly to an appreciable extent beyond the edge of the cap or cover, as shown at w^2 . 90 95 100 105

As will be apparent to those skilled in the art, the switch herein disclosed may, dependent upon the wiring with the contact supports or posts, be used as a single or a double pole switch or for a two, three and four circuit switch, etc. 110 115 120

I will not herein claim the device for connecting the pull-cord with the operating mechanism, nor the cover provided with the special insulating lining, inasmuch as these more properly constitute subjects matter for divisional applications. 125

I claim:—

1. In a switch of the character described, a shaft having a squared portion, a metal switch blade having a central opening there- 125 in larger than the squared portion of the shaft, an insulating member filling the opening in the central portion of said blade and fitting upon the squared portion of the shaft, insulating plates overlying said first 130

wheel loosely mounted on said shaft, a pawl carried by said sheave and adapted to engage said ratchet wheel, a cam plate movable with said ratchet wheel and provided with a cam slot therein, a detent carrier fixedly secured to said shaft at one side of said cam plate, a disk fixedly supported from said base and surrounding said shaft, said disk being provided with a plurality of notches 10 in the periphery thereof, a pivoted detent carried by said detent carrier and adapted to engage one of the notches in said disk, said detent being provided with a portion engaging the cam slot in the cam plate, and 15 a motor spring connecting the ratchet wheel and said detent carrier.

11. In an electrical switch, the combination with a shaft, of a switch member mounted thereon comprising a blade having an 20 opening larger than the shaft, an insulating member filling the said opening and fitting upon the shaft so as to be rotated thereby, insulating plates overlying said insulating filling member and the opposite faces of the 25 switch blade, and clamping means passing through the insulating plates and the switch blade and insulated from the latter.

12. In an electrical switch, the combination with a shaft, of a switch member mounted thereon comprising a blade having an 30

opening larger than the shaft, an insulating member filling the said opening and fitting upon the shaft so as to be rotated thereby, insulating plates overlying said insulating filling member and the opposite faces of the 35 switch blade, metal plates overlying said insulating plates, and clamping means passing through the said metal and insulating plates and the switch blade and insulated from the latter.

13. In an electrical switch, the combination with a shaft, of a switch member mounted thereon and movable longitudinally thereof for a limited distance, said switch member comprising a blade having an opening larger 40 than the shaft, an insulating member filling the said opening and fitting upon the shaft so as to be rotated thereby, insulating plates overlying said insulating filling member and the opposite faces of the switch blade, and 45 clamping means passing through the insulating plates and the switch blade and insulated from the latter.

In testimony whereof I affix my signature in presence of two witnesses.

ALLEN A. TIRRILL.
